UNITED STATES PATENT OFFICE.

NAPOLEON P. BISSONNETTE, OF BRIDGEPORT, CONNECTICUT.

ALARM FOR PORTABLE BOXES.

No. 917,991.

Specification of Letters Patent. Filed April 18, 1909.

Application filed May 26, 1908. Serial No. 496,120.

To all whom it may concern:

Be it known that I, NAPOLEON P. BISSONNETTE, a citizen of the United States, residing at Bridgeport, county of Fairfield, State of Connecticut, have invented a new and useful Alarm for Portable Boxes, of which the following is a specification.

This invention has for its object to provide a simple and inexpensive alarm adapted for general use to indicate when something is being tampered with and especially adapted for use in connection with a combination lock as an alarm for portable boxes, for example, jewelry boxes, boxes for silverware, &c.

In order to provide an alarm of this character which will be set in operation by the slightest disturbance of the box and which will ring for a long period unless stopped by a person having knowledge of the combination of the lock, I have devised the novel mechanism which I will now describe, referring to the accompanying drawing forming a part of this specification and using reference characters to indicate the several parts.

Figure 1 is a longitudinal section of a box, illustrating my novel alarm in side elevation, the section line being indicated by 1—1 in Fig. 2 and the view being in the direction of the arrows; and Fig. 2 is a transverse section on the line 2—2 in Fig. 1 looking in the direction of the arrows.

10 denotes a box of any ordinary or preferred construction and 11 a lid hinged thereto as at 12 and provided on its lower unattached edge with a locking catch indicated by 13. Upon the inner front wall of the box I place an ordinary combination lock, indicated by 14, which is provided with a spring-controlled locking bolt 15. The mechanism of the lock is not shown for the reason that specifically it forms no portion of my present invention, it being sufficient for the purposes of this specification to state that the lock has a spring-controlled locking bolt which may operate in any ordinary or preferred manner. Contiguous to the lock is a lever 16 fulcrumed on a stud 17 which projects from the inner wall of the box. A spring 18 bearing upon the under side of one arm of the lever, the left arm as shown in Fig. 1, acts to normally hold said arm in the raised position; that is, slightly raised from the position shown in Fig. 1. This spring may be a flat metal spring, as shown in the drawing, in which the spring is shown as provided with an attaching plate 19 which is secured to the

inner front wall of the box. At the extreme end of the left arm of the lever, as shown in the drawing, is a pin 20 which projects upward through a hole 21 in the dish-shaped bottom 22 of a pan 23 which is likewise secured to the inner wall of the box, as by attaching plates 24, either or both of which may be used. Within the pan is a relatively heavy ball 25, the weight of which when resting upon the pin is sufficient to hold the left end of the lever downward against the power of the spring. The condition of the ball, however, is that of unstable equilibrium and the least movement or disturbance of the box is sufficient to cause the ball to roll away from the pin which is constantly pressed upward by the spring. When the ball is displaced from the pin, therefore, the pin will rise and remain in the raised position as it is of such length or height that the ball cannot force it downward again.

26 denotes a bell secured to the inner wall of the box, 27 a clapper and 28 operating mechanism therefor which is not illustrated in detail as specifically it forms no portion of the present invention, as it is obvious that an electric or any other type of bell may be used. In the present instance I have simply indicated a case to contain spring-controlled operating mechanism, the case being secured to the inner wall of the box.

29 denotes a detent arm extending from the operating mechanism, which is engaged by the arm of lever 16 opposite to pin 20, that is the right arm of the lever as shown in the drawing. This arm of the lever is shown as suitably shaped, as at 30, to engage the detent arm and lock it in the inoperative position; that is, so that the clapper operating mechanism is locked out of operation.

31 denotes a stopping lever which is fulcrumed on a stud 32 projecting from the inner wall of the box. The lower arm of this lever is suitably shaped to engage lever 16, when said lever is in the releasing position, and the upper end of said lever is connected to an arm 33, the other end of which is pivoted to locking bolt 15, as at 34.

The operation is as follows: In Fig. 1 the locking bolt is shown in the locking position, that is in engagement with catch 13 upon the lid. Should the box be moved very slightly the effect will be to displace the ball which is resting upon the end of pin 20 and holding the left arm of lever 16 downward against the power of the spring and the right arm up-

ward which retains the detent arm in the locking position. As soon as the ball moves to the slightest extent the pin will be released and the spring will act to tilt the lever, the 5 pin moving upward in hole 21 and the right arm of the lever swinging downward and releasing the detent arm, which causes the operating mechanism to ring the bell. The ball when it settles back to place will roll against 10 the pin but cannot move the pin downward again because said pin is of such length that the ball will be stopped against one side of the pin, so that the ringing of the bell will continue until the operating mechanism if 15 controlled by a spring has run down, or if electric ringing mechanism is used, so long as the battery holds out unless it is stopped by the operation of the lock. A person knowing the combination can stop the ringing of the 20 bell by setting up the combination and moving the locking bolt to the unlocking position; that is, toward the left from the position shown in Fig. 1. The movement of the locking bolt to the unlocking position swings the 25 stopping lever and moves the lower end of said lever, which is now in engagement with lever 16, downward, swinging the right end of lever 16 upward which raises the detent arm and stops the ringing of the bell. The 30 oscillation of lever 16 moves pin 20 downward to the position shown in Fig. 1 against the power of the spring and permits the ball to roll to its normal position on top of and in engagement with the end of the pin, as in the 35 drawing, and retains the parts in this position against the power of the spring until the ball is again displaced.

Having thus described my invention, I claim:

40 1. An alarm of the character described comprising bell mechanism having a detent arm, a pan having a dish-shaped bottom with a central hole, a ball in said pan, a lever one arm of which engages the detent arm the 45 other arm being provided with a pin projecting through the hole in said pan to be engaged by the ball to lock the bell mechanism out of operation, and means for tilting the lever and releasing the bell mechanism when the ball 50 is displaced from the end of the pin, the pin being of a length to form a stop to prevent the ball from rolling back over it when said pin is raised.

55 2. An alarm of the character described comprising bell mechanism having a detent arm, a pan having a dish-shaped bottom with a central hole, a ball in said pan, a lever one arm of which engages the detent arm the other arm being provided with a pin project- 60 ing through the hole in said pan to be engaged by the ball to lock the bell mechanism out of operation, and a spring bearing upon

one arm of the lever to tilt said lever and release the bell mechanism when the ball is displaced from the end of the pin, the pin being 65 of a length to form a stop to prevent the ball from rolling back over it when said pin is raised.

3. An alarm of the character described comprising bell mechanism having a detent arm, a pan having a dish-shaped bottom with a central hole, a ball in said pan, a lever one arm of which engages the detent arm the other arm being provided with a pin projecting through the hole in said pan to be engaged by the ball to lock the bell mechanism out of operation, means for tilting the lever and releasing the bell mechanism when the ball is displaced from the end of the pin, the pin being of a length to form a stop to prevent the ball from rolling back over it when said pin is raised, and means for returning the lever to its normal position against the power of the spring and permitting the ball to again engage the end of the pin. 80

4. An alarm of the character described comprising bell mechanism having a detent arm, a pan having a dish-shaped bottom with a central hole, a ball in said pan, a lever one arm of which engages the detent arm the 90 other arm being provided with a pin projecting through the hole in said pan to be engaged by the ball to lock the bell mechanism out of operation, means for tilting the lever and releasing the bell mechanism when the 95 ball is displaced from the end of the pin, a stopping lever for returning the lever to its normal position, a locking bolt and a connection between the locking bolt and the stopping lever. 100

5. An alarm of the character described comprising bell mechanism having a detent arm, a pan having a dish-shaped bottom with a central hole, a ball in said pan, a lever one arm of which engages the detent arm and the 105 other arm being provided with a pin projecting through the hole in said pan to be engaged by the ball to lock the bell mechanism out of operation, means for tilting the lever and releasing the bell mechanism when the 110 ball is displaced from the end of the pin, the pin being of a length to form a stop to prevent the ball from rolling back over it when said pin is raised, a stopping lever one end of which is adapted to engage the lever, for the 115 purpose set forth, a locking bolt and an arm pivoted to the locking bolt and connected to the stopping lever.

In testimony whereof I affix my signature, in presence of two witnesses.
